U. S. PATENT OFFICE.

No. 25.

1861.

WHOLE No. 1,390.

Clock Case.

E. C. BREWSTER, OF BRISTOL, CONNECTICUT.

Letters Patent for a Design No. 25, dated March 19, 1861.

SPECIFICATION.

TO ALL WHOM IT MAY CONCERN:

Be it known, that I, E. C. BREWSTER, of Bristol, county of Hartford, and State of Connecticut, have invented or produced a new and original Design for a Clock Case; and I do hereby declare that the following is a full and exact description of the same, referring to the photographic views, in which the same letters indicate like parts.

In the accompanying photographic view is shown a new and original design for a clock case.

A is a square edge base.

B is a square edge rounded top frame or case, configurated with columns C, and circular rounded arch D. E is a plane recess surface configurated with plane rounded sashes F and G. The whole combined to produce an ornamental design for a clock case.

What I claim, therefore, and desire to secure by Letters Patent, is—

The design for a clock case, as herein above illustrated and set forth.

E. C. BREWSTER.
